US0D1108230S

(12) **United States Design Patent** (10) Patent No.: **US D1,108,230 S**
(45) Date of Patent: ** Jan. 6, 2026

(54) **SHOVEL**

(71) Applicant: **GARANT GP**,
Saint-Francois-de-la-Riviere-du-Sud
(CA)

(72) Inventors: **Felix Marin Dempsey**, Donnacona
(CA); **Carl Blouin**, Levis (CA);
Francois Dallaire, Beaumont (CA)

(73) Assignee: **GARANT GP**,
Saint-Francois-de-la-Riviere-du-Sud
(CA)

(**) Term: **15 Years**

(21) Appl. No.: **29/943,717**

(22) Filed: **May 23, 2024**

(51) LOC (15) Cl. **08-01**

(52) U.S. Cl.

USPC **D8/10**

(58) **Field of Classification Search**

USPC D8/1, 10, 14; D15/11, 32

CPC A01B 1/02; A01B 1/026; E01H 5/02

See application file for complete search history.

(57) **CLAIM**

The ornamental design for a shovel as shown and described.

DESCRIPTION

FIG. 1 is a perspective view of the shovel showing our new design;

FIG. 2 is a front view of the shovel;

FIG. 3 is a rear view of the shovel;

FIG. 4 is a first side view of the shovel;

FIG. 5 is a second side view of the shovel;

FIG. 6 is a top view of the shovel; and,

FIG. 7 is a bottom view of the shovel.

The broken lines shown in the drawings illustrate portions of the shovel that form no part of the claimed design.

1 Claim, 7 Drawing Sheets
